CHEST FREEZER CONTROL PANEL

Montgomery Ferar, Huntington Woods, Mich., assignor
to Whirlpool Corporation, St. Joseph, Mich., a cor-
poration of Delaware

Application March 25, 1958, Serial No. 50,170

Term of patent 14 years

(Cl. D67—3)

Figure 1 is a top elevational view of a chest freezer control panel, showing my new design;

Figure 2 is a front elevational view of the same;

Figure 3 is an end elevational view of the same;

Figure 4 is a sectional view on the line 4—4 of Figure 2;

Figure 5 is a sectional view on the line 5—5 of Figure 2;

Figure 6 is a sectional view on the line 6—6 of Figure 2; and

Figure 7 is a sectional view on the line 7—7 of Figure 2.

I claim:

The ornamental design for a chest freezer control panel, as shown.
